UNITED STATES PATENT OFFICE.

EDWARD MAGUIRE, OF LEMONT, ILLINOIS.

FIRE-EXTINGUISHER FOR CAR-HEATERS.

SPECIFICATION forming part of Letters Patent No. 374,745, dated December 13, 1887.

Application filed April 26, 1887. Serial No. 236,185. (No model.)

To all whom it may concern:

Be it known that I, EDWARD MAGUIRE, of Lemont, in the county of Cook and State of Illinois, have invented a new and Improved 5 Fire-Extinguisher for Car-Heaters, of which the following is a full, clear, and exact description.

The object of my invention is to provide a new and improved fire-extinguisher for car- 10 heaters, to extinguish the fire in the heater when the latter is upset by a collision or other accident.

The invention consists in the construction and arrangement of parts and details and combinations of the same, as will be fully described hereinafter, and then pointed out in the claim.

Reference is to be had to the accompanying drawings, forming a part of this specification, 20 in which similar letters of reference indicate corresponding parts in both the figures.

Figure 1 is a longitudinal sectional elevation of a car provided with my improvement, with the tank partly in section; and Fig. 2 is a sectional plan view of the same.

In the car A is placed the car-heater B, of any approved construction. Into the fire-box of the heater B leads the pipe C, connected by the flexible tube D with the outlet-pipe E, secured in the middle to the perforated bottom F of the tank G, supported on suitable braces above the heater B.

In the tank G is secured the false bottom H, held a short distance above the perforated bottom F, and provided in its middle with an opening adapted to be closed by a plug or stopper, I, to the upper end of which is secured one end of the wire or rope J, extending upward through the top of the tank G and 35 passing over a swivel-pulley, K, secured to roof of the car A. The wire or rope J then passes downward, and is secured with its end to the heater B in any convenient manner. The top of the tank, G, is provided with an 40 inlet-opening, G', adapted to be closed by cap. The tank G, above the false bottom H, is filled with a fire-extinguishing fluid, which is introduced through the inlet G'.

To the upper end of the stopper or plug I 45 is also secured one end of the rope L, leading upward and passing over the pulley K and

over a second pulley, N, located some distance away from the heater B, and also secured to the roof or the side of the car A. The rope L then passes downward and hangs with its 55 lower end within convenient reach of the passenger.

The operation is as follows: When the car-heater A is upset by a collision or other accident, then the heater, in the act of falling, 60 pulls on the wire or rope J, thus pulling the plug or stopper I out of the center opening in the false bottom H, whereby part of the fire-extinguishing fluid in the tank G passes through the pipes E, D, and C into the fire-box of the heater A and extinguishes the burning fuel in the heater. Part of the fire-extinguishing fluid passes through the perforated bottom F and spreads over the outside of the heater, thus cooling the heater, and also extinguishing any burning fuel which may have passed out through the doors of the heater. In case the heater B is not upset, but there is a danger through certain causes that the heater 70 may set fire to the car, then if one of the passengers pulls on the rope L the plug or stopper I is withdrawn from the false bottom H, and the fire-extinguishing fluid in the tank G 75 will then also act, as above described.

Having thus fully described my invention, I 80 claim as new and desire to secure by Letters Patent—

The combination, with the car-heater B, having a pipe, C, leading through it into the combustion-chamber, of the tank G, secured to the 85 car above and to one side of the heater and provided with an apertured false bottom, H, having a valve or plug, I, the foraminated bottom F, below the false bottom and provided with an outlet-pipe, E, the pipe D, connecting 90 said outlet with the pipe C, and the operating-cord connected to the plug and leading out through the tank, whereby when the plug is withdrawn the contents of the tank will flow into the car through the foraminated bottom 95 and into the heater through the pipe D, substantially as set forth.

EDWARD MAGUIRE.
